FORK OR SIMILAR ARTICLE

John C. Tatum, 224 Ryan Ave., St. Paul, Minn.

Filed June 17, 1963, Ser. No. 75,387

Term of patent 14 years

(Cl. D54—12)

FIG. 1

The design is intended for use on sets comprising forks, spoons and similar articles of flatware. The dominant features of my design reside in the particular handle portion which is decorated and ribbed as shown.

I claim:

The ornamental design for a fork or similar article, as shown and described.
